CLAIM

I claim the ornamental design for a hand-held water filter, as shown and described.

DESCRIPTION

FIG. 1 is a front perspective view of a hand-held water filter showing my new design, in a first use configuration; FIG. 2 is a rear view of the hand-held water filter of FIG. 1; FIG. 3 is a front view of the hand-held water filter of FIG. 1; FIG. 4 is a left side view of the hand-held water filter of FIG. 1; FIG. 5 is a right side view of the hand-held water filter of FIG. 1; FIG. 6 is a top view of the hand-held water filter of FIG. 1; FIG. 7 is a bottom view of the hand-held water filter of FIG. 1; and, FIG. 8 is a front perspective view of the hand-held water filter of FIG. 1, in a second use configuration. The shade lines shown in the drawings indicate the character and contour of surfaces represented and should not be confused with surface ornamentation. The use of broken lines in certain of the Figures indicates that the portion of the article depicted in broken lines forms no part of the design.
